UNITED STATES PATENT OFFICE.

CLAUDE M. JOHNSON, OF NEW YORK, N. Y., ASSIGNOR TO UNSINKABLE BATHING BOAT COMPANY, INC., A CORPORATION OF NEW YORK.

BATHING-BOAT.

1,080,635.

Specification of Letters Patent.

Patented Dec. 9, 1913.

Application filed September 23, 1912. Serial No. 721,851.

To all whom it may concern:

Be it known that I, CLAUDE M. JOHNSON, a citizen of the United States, and a resident of the city of New York, borough of 5 Manhattan, in the county and State of New York, have invented a new and Improved Bathing-Boat, of which the following is a full, clear, and exact description.

Among the principal objects which the 10 present invention has in view are: to provide a boat of the character mentioned, having a supporting section which may be submerged at will, to form an inclosed bathing area arranged to prevent accident to the 15 bather; to provide a pleasure boat having a deck through which water freely passes, and means for, at will, submerging a portion of the deck, for bathing purposes; to provide a boat of the character mentioned with 20 a motor-actuated propelling means; and to provide means for steering or guiding a boat of the character mentioned.

Reference is to be had to the accompanying drawings forming a part of this specification, in which similar characters of reference indicate corresponding parts in all the views, and in which—

Figure 1 is a side elevation of a boat constructed and arranged in accordance 30 with the present invention, showing in dotted lines the bathing deck in its raised position; Fig. 2 is a longitudinal vertical section taken on the line 2—2 in Fig. 3, showing in full lines the bathing deck in lowered position; Fig. 3 is a plan view of a boat constructed and arranged in accordance with the present invention; Fig. 4 is a vertical section taken on the line 4—4 in Fig. 1; Fig. 5 is a vertical section taken on 35 the line 5—5 in Fig. 2; Fig. 6 is a longitudinal vertical section of a modified form of the invention; and Fig. 7 is a cross section of a fragment of the structure shown in Fig. 6, the section being taken on the line 40 7—7 in Fig. 6.

As shown in the accompanying drawings, the boat is provided with two air-tight hulls 10, structurally connected and held in parallel relation as in a catamaran. The hulls 50 are each provided with a keel 11, upon which is mounted a rudder 12. The hulls are each provided with stanchions 13, said stanchions being erected on the gunwale of each hull

at the side adjacent the other hull. The stanchions 13 are connected at the top by 55 rails 14, and are held in position by braces 15 and 16. The end stanchions 13 of both hulls are connected by cross rails 17 and 18. The rails 17 and 18 are suitably maintained on the hulls 10 in relatively rigid parallel 60 arrangement. In this, the rails 17 and 18 are assisted by deck-beams 19, 19 and 20. Said deck-beams are crossed by deck-planks 21, which are laid fore and aft and are spaced apart, as best seen in Fig. 3 of the 65 drawings, to provide for the quick drainage of any water taken upon the deck. As seen best in Figs. 2 and 3 of the drawings, the main deck is that formed by the planks 21 and mounted upon the deck-beams 19, 19 70 and 20.

Forward of the main deck above described is an auxiliary or bathing deck, composed of planks 22, which, as shown in Fig. 3 of the drawings, are disposed crosswise and 75 securely fastened to stringers 23. The bathing deck thus formed is provided with suitable hinges 24 mounted upon the rail 18, adjacent the bow of the boat. It is the purpose to permit the rear end of the bathing 80 deck to drop into, and to be submerged in, the water, to be supported there by a cable 25 and an apron formed by slats 26 and the header 27 thereof. The apron formed by the slats 26 is pivotally secured to the deck-beam 20 by means of hinges 28. This position of the hinges 28 is such that when the apron is lifted to a horizontal position, it rests snugly beneath the forward deck-beam 19. The header 27 of said apron is so arranged that it extends below the stringers 23, while a cleat 29, with which the stringers 23 is provided, extends beneath the slats 26 of the apron. Mounted upon the cleat 29 are pulleys 30, under which is reeved the cable 90 25. The cable 25 is wound upon a drum 31, having a manually-operative crank handle 32. It is obvious that when the handle 32 is manipulated to wind the cable 25 on the drum 31, the cleat 29 lifts the apron and the 100 slats 26 thereof as the bathing deck is lifted. Connected with the handle 32 is a ratchet wheel 33. To engage the teeth of the wheel 33, there is provided a pawl 34, which is adapted to hold the drum 31 and cable 25 105 connected therewith in any desired position,

to immerse the bathing deck to greater or lesser depth.

The bathing deck is normally supported by uprights 35, which are mounted upon the 5 external stringers 23 of said deck and are reinforced by braces 36. The uprights 35 are constructed from superposed braces spaced apart to straddle the rails 14, as best shown in Figs. 4 and 5 of the drawings.

10 Said uprights are provided with a series of perforations 37 which are adapted to register with perforations 38 in the rails 14. To secure in holding relation the uprights 35 and rails 14, there is provided for each upright a pin 39. As an additional reinforce for the uprights 35, the tie-rods 40 are furnished, which connect the tops of the uprights 35 and the outer ends of the stringers 23.

20 As will be observed by reference to Fig. 2 of the drawings, when the bathing deck is in the lowered position, as therein shown, the braces 36, 36 and the tie rods 40 constitute at each side or edge of the bathing deck, a rail, which, when the boat is in service, prevents a person resting on the bathing deck from being swept below the hulls 10.

The boat above described is driven by a motor, which is shown as being mounted 30 within a motor casing 41. The casing 41 is provided to preserve the motor from contacting with the flying water. The motor drives the shaft 42, which, as seen best in Figs. 2 and 3 of the drawings, is suspended 35 between the hulls 10, there being provided for this purpose a bracket arm 43, at the end whereof is formed a bearing 44. At the end of the shaft 42, a propeller 45 is mounted. The motor is of the internal combustion 40 type, and the fuel for said motor is carried in a tank 46, disposed at the end of the vessel.

It will be understood that the boat herein described is intended as a pleasure craft, 45 and is to be employed as a pleasure-giving device for bathers. The person steering the boat is provided with a seat 47 adjacent the steering wheel 48. The steering wheel 48 is, for convenience, mounted upon the motor casing 41. The rudders 12 are connected by a spreader bar 49. The spreader bar 49 is suitably provided with eyelets 50, 50, which are employed for attaching the ends of a cable 51. The cable 51 is reeved over guide 55 pulleys 52, and is wound upon the windlass connected with the wheel 48. Under usual service conditions, the occupants of the boat are costumed in bathing suits, so that the wash or splash of the water does no damage. 60 The motor is started, and the boat is driven by the propeller 45, and guided by manipulation of the wheel 48. At any time, the occupants of the boat may, by releasing the pawl 34 from the ratchet wheel 33, permit

the bathing deck at the forward end of the 65 boat to drop to the position shown in Fig. 2 of the drawings. The bather now, by stepping onto the inclined deck formed by the planks 22, is immersed in the water. If the boat be in motion, it will be seen that 70 the person receives a sensation as if swimming rapidly through the water. When the speed of the boat is increased, the bather, by grasping with his hands the planks 22, may permit as much of his body to be immersed 75 within the rushing water as he desires. The depth, to within certain fixed limits, of the water above the bathing deck, may be regulated or controlled by setting said deck and the uprights 35 thereof by means of the pins 80 39. The sensation of being carried rapidly through the water, as such a boat is capable of producing is an exciting and agreeable one. When it is desired that the bathing shall be discontinued, the bathing deck is 85 raised, the attendant, for this purpose, manipulating the handle 32 until the stringers 23 are raised to a horizontal position, to rest snugly below the forward rail 18 and the forward deck beam 19. 90

During the operation of bathing as above described, the danger of accident is eliminated by the apron formed by the slats 26, which, if the bather loses his grip of the planks 22, saves him from being washed 95 rearward off said boat. The safety elements of the braces 36, the uprights 35 and the tie-rods 40 has been above alluded to. Thus, it is arranged that if a bather should lose his grip upon the planks 22 and be swept 100 therefrom, he is prevented from being lost by said apron and the side members referred to. In the raised position of the bathing deck, the apron 26 is likewise raised, and the washway for the water between the hulls 105 10, 10 is clear. The boat is now freed from any drag which would impede its headway, and may then be used for cruising.

In the modified form of the invention as disclosed in Figs. 6 and 7, a horizontal staging is shown, which forms, when raised, the deck between the hulls 10, and when submerged, the floor of the submerged portion of the vehicle. This staging is constructed from a number of parallel rails 53, connected transversely by slats 54. Adjacent both ends of the vessel are provided aprons constructed from the stringers 23 and the planks 22. The staging formed by the rails 53 and the slats 54 is supported at either 110 side by a frame having vertical rails 55, connected at the upper and lower ends by cross rails 56. On each of the cross rails 56 are mounted pulleys 57. Over the pulleys 57 is extended a continuous belt cable 58. 115 The cable 58 is given two or more wraps upon a winch pulley 59 mounted in the side rail 14 of the vessel. The shaft 60 of the 120

pulley 59 is furnished with a crank handle 61, by which the said shaft and pulley mounted thereon are manipulated. The frames formed by the rails 55 and 56 are 5 guided in their vertical movement by guide rollers 62 and 63, the former being rotatively mounted on the hulls 10, and the latter similarly mounted on the rails 14. The rollers 62 and 63 are so exposed that the

10 movement of the frame is accurately perpendicular to the hulls 10, holding the staging connected therewith parallel to the surface of the water in which the hulls are floated. To brace the staging and the rails 15 53 thereof, I have furnished truss rods 64.

When the invention is constructed in the modified form shown in Figs. 6 and 7, the attendant may at any time, by turning the winch pulley 59, raise or lower the staging, 20 to vary the depth of submergence of said staging. In this manner, the staging may be arranged for small children or for adults. By lifting the staging to a level flush with the decks of the hulls 10, said staging serves

25 as a convenient deck for the entire vessel. In this position, the stringers 23 are held in parallel relation to the rails 53, said stringers sliding between the end slats 54, which are superposed on the rails 53.

30 In the modified form of the invention as shown in Fig. 6, the propeller 45 is preferably mounted on a shaft 66 mounted in bearings at the lower end of the suspension frame 67. The frame 67 is suspended from 35 deck-beams 68, upon which are carried the motor housing 69 and pilot's seat 70. The pilot's seat is suitably disposed with reference to the steering wheel 48. It will be noted that the propeller 45 is mounted at 40 the forward end of the shaft 66, this arrangement providing the preferred condition of operation of the propeller; that is, where the propeller operates in clear weather. At the opposite or following end of 45 the shaft 66 is provided a miter wheel 71, which is constantly engaged by a mated wheel 72 on the driving shaft 73 operatively connected with the motor in the housing 69.

The operation and employment of the 50 modified form of the invention is in all essentials the same as that above described with reference to the preferred form.

In some cases, and particularly in large boats, such as herein referred to as the modified form shown in Figs. 6 and 7, I provide and employ ladders 74. The ladders 74 are used by bathers who see fit to swim off from the deck of the boat. These ladders are provided with hinges 75 at the edge of the hulls 55 10. The upper ends of the strings of the ladders are chamfered to form a surface 76, which permits the ladders to rest over against the rails 14 when the ladders are housed, as shown at the right side of Fig.

7 of the drawings. It will be understood 65 that while I have shown the ladders 74 as applied to the modified form only, the same may be applied to the preferred form without varying the spirit of the invention.

Having thus described my invention, I 70 claim as new and desire to secure by Letters Patent:—

1. A boat of the character mentioned, comprising a plurality of hulls; a framing structure rigidly connecting said hulls in spaced-apart and parallel relation; a main deck rigidly mounted upon, and bridging the space between, said hulls; a bathing deck pivotally mounted upon said framing structure to move vertically between said hulls; 80 means mounted upon said hulls for raising and lowering the rear end of said bathing deck to submerge the same; and an apron pivotally mounted upon said main deck and loosely connected with said bathing 85 deck to extend across the space between said decks when the bathing deck is submerged.

2. A bathing boat, comprising a plurality of floating hulls, spaced apart; a deck member pivotally mounted upon and at the forward end of said hulls and at approximately the deck level thereof; means for lowering the free end of said deck member below the water in which said hulls are 90 floated; hand holds mounted on said deck member to be gripped by a person bathing; and means for propelling said hulls to float the body of a bather from said deck member. 95

3. A bathing boat, comprising a plurality of floating hulls, spaced apart; an inclined deck connecting said hulls and rearwardly depressed, said deck being inclined, to form a rest for the body of a bather when the boat is at rest or slowly moved; hand-holds 100 mounted on said deck to be gripped by a bather; and means for propelling said boat with force sufficient to lift the body of the bather from said deck. 105

4. A bathing boat, comprising a plurality of floating hulls, spaced apart in parallel relation; an inclined perforated deck connecting said hulls, the forward end of said deck being near the water-level, and the rear end of said deck being depressed; means 110 provided on said deck for the convenience of a bather to grip the same; and means for propelling said boat through the water with force sufficient to lift the body of the bather off said inclined deck. 115

5. A bathing boat, comprising a plurality of floating hulls, spaced apart in parallel relation; a deck uniting said hulls and having a rigid and a movable section, said sections being arranged longitudinally; means 120 for depressing the rearward end of said movable section to extend the desired distance below the water-level, said movable 125

section being perforated to permit the water to pass freely therethrough, means forming hand-grips for a bather to hold said movable section; and means for propelling the boat 5 through the water with force sufficient to lift the body of the bather from said movable section.

6. A bathing boat, comprising a plurality of floating hulls spaced apart in parallel relation; a deck uniting said hulls, and having a rigid and a movable section, said sections being arranged longitudinally; means for depressing the rearward end of said movable section to extend the desired distance below the water-level, said movable section being perforated to permit the water to pass freely therethrough; means forming hand-grips for a bather to hold said movable section; means connected with the rear end 15 of the movable section extending above the water-level to prevent the loss of a bather if disengaged from said movable section; and a connective structure embodying suitably perforated aprons uniting said rigid and 20 movable sections at the rear of said movable section to catch a floating body when disengaged from said movable section.

7. A bathing boat, comprising a plurality of floating hulls spaced apart in parallel 30 relation; a rigid deck section uniting said hulls above the water level; an auxiliary deck pivotally mounted upon and connecting said hulls forward of said rigid deck section and at a level therewith; and means for 35 elevating the rear end of said auxiliary deck to a level with said rigid deck section.

8. A bathing boat, comprising a plurality of floating hulls spaced apart in parallel relation; a rigid deck section uniting said 40 hulls above the water level; an auxiliary deck pivotally mounted upon and uniting said hulls forward of said rigid deck section and at a level therewith; means for elevating the rear end of said auxiliary 45 deck to a level with said rigid deck section; and an apron pivotally connected with said rigid deck section and loosely connected with said auxiliary deck, said apron form-

ing a guard to prevent the loss of a bather if disengaged from said auxiliary deck. 50

9. A bathing boat, comprising a plurality of floating hulls spaced apart in parallel relation; a connective structure for said hulls, embodying a rigid deck section extending therebetween above the water-level of said 55 hulls; an auxiliary deck section pivotally mounted above said hulls, at the forward end thereof, at approximately the level of said rigid deck section; a perforated apron pivotally mounted upon said rigid deck section and loosely connected with the free end of said auxiliary deck section; means mounted on said hulls for submerging the rear end of said auxiliary deck section; means providing hand-holds on said auxiliary deck section, for bathers to hold thereto; and means for propelling said boat with 60 force sufficient for the water to lift the body of the bather from said auxiliary deck section. 65

10. A bathing boat, comprising a plurality of floating hulls spaced apart in parallel relation; a connective structure for said hulls, embodying a rigid deck section extending therebetween above the water-level 75 of said hulls; an auxiliary deck section pivotally mounted above said hulls, at the forward end thereof, at approximately the level of said rigid deck section; a perforated apron pivotally mounted upon said rigid 80 deck section and loosely connected with the free end of said auxiliary deck section; means mounted on said hulls for submerging the rear end of said auxiliary deck section; means providing hand-holds on said auxiliary deck section, for bathers to hold thereto; and means for locking said auxiliary deck section in inclined position. 85

In testimony whereof I have signed my name to this specification in the presence of 90 two subscribing witnesses.

CLAUDE M. JOHNSON.
